APPARATUS FOR HOT ROLLING

William L. Roberts, Murrysville, Pa., assignor to United States Steel Corporation, a corporation of New Jersey
Filed Feb. 18, 1963, Ser. No. 259,249
6 Claims. (Cl. 72—12)

This invention relates to apparatus for hot rolling and more particularly to hot rolling structural shapes and slabs. Because of non-uniformity of temperature throughout the workpiece and the lack of symmetry in roll pass design a workpiece such as I-beams or slabs may curve upwardly or downwardly as they leave the mill. Workpieces which have appreciable curvature as they leave a roll stand produce considerable wear on the guides and strippers of the mill and may not satisfactorily enter a succeeding roll stand for further reduction. This often results in a cobble. In order to eliminate these difficulties the present practice is to straighten curved workpieces prior to their entering subsequent processing equipment. This adds to the expense of manufacture and if the workpiece is a structural beam of high strength alloy the straightening operation is a difficult one.

It is therefore an object of my invention to provide apparatus for hot rolling a workpiece in such a manner that it will be commercially straight as it leaves the mill.

This and other objects will be more apparent after referring to the following specification and attached drawings, in which:

FIGURE 1 is a somewhat schematic side elevation, partly in section, of the apparatus of my invention; and

FIGURE 2 is a schematic view of the hydraulic system of my invention.

Referring more particularly to the drawings reference numeral 2 indicates the housing of a mill stand. This may be the final stand or an intermediate stand of the mill. Upper roll 4 and lower roll 6 have their ends supported in the usual manner by roll chocks 8, 9, 10 and 11, respectively. A bearing plate 12 is provided above the chock 8 and an adjusting screw 14 passing through the top of the housing 2 bears against the bearing plate 12. A similar construction is provided above the chock 9. According to my invention I provide hydraulic cylinders 16 and 17 for receiving the entry and exit sides of chock 8 and hydraulic cylinders 18 and 19 for receiving the entry and exit sides of chock 9. Similarly hydraulic cylinders 20, 21 and 22, 23 are provided for chocks 10 and 11, respectively. Supports 24 and 26 are arranged on the exit side of the mill, one above and one below the roll pass, and extend from side to side of the mill housing 2 to which they are attached. A load cell 28 and stripper 30 are supported by the upper support 24 and a similar load cell 32 and stripper 34 are supported by the lower support 26. Any suitable load cell, such as a "Pressductor," which generates an electric signal may be used. Fluid for the cylinders 16 to 23 is delivered through conduits 36 to 41, respectively. Conduits 36, 38, 41 and 43 are connected to a conduit 44 and conduits 37, 39, 40 and 42 to a conduit 45. A hydraulic relay or valve 52 controls the flow of fluid to and from the cylinders. Valve 52 consists of a casing 54 having ports 56, 58, 60, 62 and 64. Ports 56 and 58 are connected to return the fluid to its supply (not shown) and port 60 is connected to the high pressure supply system. A rod 66 having spools 68 and 70 thereon is slidably mounted in the casing 54 and extends from one end thereof. A spring 72 is connected to the end of rod 66 and coils 74 and 76 surround the rod 66 on each side of a magnetic core 78 attached to the rod 66. The spring 72 will hold the rod 66 in the position shown when neither coil 74 or 76 is energized. The coil 74 is connected to the output of an

2

amplifier 80 connected to the output of lower load cell 32. The coil 76 is connected to an amplifier 82 which is connected to the output of upper load cell 28. Rectifiers 84 and 86 are provided in the circuits to coils 74 and 76, respectively.

In operation, if the workpiece W is straight as it leaves the mill stand, the parts will be in the position shown. However, if the workpiece curves upwardly the upper load cell 28 becomes loaded and produces an electric signal proportional to the load. This signal is amplified and transmitted to coil 76 so as to energize the same. Energization of coil 76 moves the core 78 and spools 68 and 70 to the right a distance proportional to the electric signal produced by the load cell. This causes the spool 70 to uncover a portion of port 64, thus permitting fluid under pressure to flow through ports 60 and 64, and conduits 44, 36 and 38, 41 and 43 to the cylinders 16, 18, 21 and 23, thus moving the lower roll 6 horizontally toward the entry end of the mill and the upper roll 4 toward the exit end of the mill. This will cause a straightening of the workpiece. As the work rolls are displaced hydraulic fluid is forced out of the cylinders 17, 19, 20 and 22 through ports 62 and 56 and returned to the supply system.

If the workpiece curves downwardly, the lower load cell 32 becomes loaded so that coil 74 will be energized to move the core 78 and spools 68 and 70 to the left a distance proportional to the electric signal. This causes the spool 68 to uncover a portion of port 62 and thus allow pressure fluid to pass to cylinders 17, 19, 20 and 22 so as to move the upper roll 4 toward the entry side of the mill and lower roll 6 toward the exit side of the mill and thus straighten the workpiece.

While one embodiment of my invention has been shown and described, it will be apparent that other adaptations and modifications may be made without departing from the scope of the following claims.

I claim:

1. Apparatus for hot rolling a workpiece which comprises upper and lower rolls between which the workpiece passes and is reduced, means for moving the top roll horizontally toward and away from the exit side of the rolls, means for moving the bottom roll horizontally toward and away from the exit side of the rolls, and means responsive to the workpiece leaving the rolls for actuating said roll moving means when the workpiece leaving the rolls curves away from the horizontal.

2. Apparatus for hot rolling a workpiece which comprises upper and lower rolls between which the workpiece passes and is reduced, means for moving the top roll horizontally toward and away from the exit side of the rolls, means for moving the bottom roll horizontally toward and away from the exit side of the rolls, means for determining upward curvature of the workpiece leaving the rolls, means responsive to said last named means for actuating said roll moving means to move the upper roll toward the exit side of the rolls and the lower roll toward the entry side of the rolls, means for determining downward curvature of the workpiece leaving the rolls, and means responsive to said last named means for actuating said roll moving means to move the upper roll toward the entry side of the rolls and the lower roll toward the exit side of the rolls.

3. Apparatus for hot rolling a workpiece which comprises upper and lower rolls between which the workpiece passes and is reduced, chocks on each end of each roll for rotatably supporting the same, a pair of hydraulic cylinders associated with each chock one on the entry side and one on the exit side thereof for moving the associated chock horizontally, means for controlling flow of fluid to said cylinders, and means responsive to the workpiece leaving the rolls for actuating said fluid flow control means

when the workpiece leaving the rolls curves away from the horizontal.

4. Apparatus for hot rolling a workpiece which comprises upper and lower rolls between which the workpiece passes and is reduced, chocks on each end of each roll for rotatably supporting the same, a pair of hydraulic cylinders associated with each chock one on the entry side and one on the exit side thereof for moving the associated chock horizontally, means for controlling flow of fluid to said cylinders, means for determining upward curvature of the workpiece leaving the rolls, means responsive to said last named means for actuating said fluid flow control means to move the upper roll toward the exit side of the rolls and the lower roll toward the entry side of the rolls, means for determining downward curvature of the workpiece leaving the rolls, and means responsive to said last named means for actuating said fluid flow control means to move the upper roll toward the entry side of the rolls and the lower roll toward the exit side of the rolls.

5. Apparatus for hot rolling a workpiece which comprises upper and lower rolls between which the workpiece passes and is reduced, chocks on each end of each roll for rotatably supporting the same, a pair of hydraulic cylinders associated with each chock one on the entry side and one on the exit side thereof for moving the associated chock horizontally, means for controlling flow of fluid to said cylinders, means for determining upward curvature of the workpiece leaving the rolls, a circuit actuated by said last named means for actuating said flow control means to deliver fluid under pressure to the hydraulic cylinders on the entry side of the upper chocks and the exit side of the lower chocks, means for determin-

ing downward curvature of the workpiece leaving the rolls, and a circuit actuated by said last named means for actuating said flow control means to deliver fluid under pressure to the hydraulic cylinders on the exit side of the upper chocks and the entry side of the lower chocks.

6. Apparatus for hot rolling a workpiece which comprises upper and lower rolls between which the workpiece passes and is reduced, chocks on each end of each roll for rotatably supporting the same, a pair of hydraulic cylinders associated with each chock one on the entry side and one on the exit side thereof for moving the associated chock horizontally, means for controlling flow of fluid to said cylinders, an upper stripper mounted at the exit side of said rolls, a lower stripper mounted at the exit side of said rolls, a load cell connected to be actuated by said upper stripper, a load cell connected to be actuated by said lower stripper, a circuit connected to the output of said upper load cell for actuating said flow control means to deliver fluid under pressure to the hydraulic cylinders on the entry side of the upper chocks and the exit side of the lower chocks, and a circuit connected to the output of said lower load cell for actuating said flow control means to deliver fluid under pressure to the hydraulic cylinders on the exit side of the upper chocks and the entry side of the lower chocks.
